FAULT DETECTOR AND STOPPING DEVICE
FOR TEXTILE MACHINESWillard W. Bardsley, Providence, R. I., assignor to
Wardwell Braiding Machine Company, Central
Falls, R. I., a corporation of Maine

Application June 6, 1938, Serial No. 212,028

13 Claims. (Cl. 96—19)

This invention relates to improvements in braiding, knitting, circular weaving and like machines and particularly to means for arresting the operation of the machine when imperfections occur in the fabric being produced.

One object of the invention is to provide a mechanical inspecting device or detector for machines of the type indicated for detecting imperfections in the fabricated product and acting, upon occurrence thereof, to actuate automatically the stopping mechanism of the machine to arrest its operation.

Another object of the invention is to provide a machine of the type indicated capable of braiding, knitting or otherwise forming a fabric from a plurality of strands and having means for automatically arresting the braiding or other operation when one or more of the strands becomes looped, snarled or otherwise improperly meshed in or applied to the fabric.

Another object of the invention is to provide a machine of the type indicated employing a detector or loop-catcher adapted to engage imperfections occurring in the fabric and moved into position to close an electrical circuit for energizing the stopping mechanism to arrest the operation of the machine.

Another object of the invention is to provide a device of the type indicated which is simple in construction, positive in action, and proof against derangement or getting out of order.

Another object of the invention is to provide a device of the type indicated which may be readily applied to machines already in use without material change in the structure or arrangement thereof.

Further objects of the improvement are set forth in the following specification which describes a preferred embodiment of the invention, by way of example, as illustrated by the accompanying drawings. In the drawings:

Fig. 1 is a front elevation of a conventional type of braiding machine showing the present improved fault-detector and stop-device applied to use therewith;

Fig. 2 is an enlarged part-sectional plan view of the stopping mechanism of the machine showing the relationship of the parts thereof when the machine is operative;

Fig. 3 is a side elevation of the stopping mechanism with the parts shown in the same relationship as in Fig. 2;

Fig. 4 is a similar side elevational view show-

ing the parts in position to effect stopping of the machine;

Fig. 5 is an axial sectional view through the detector or loop-catching device showing the relationship of the parts under normal operation of the machine during absence of faults or irregularities in the fabric;

Fig. 6 is a view similar to Fig. 5 showing the relationship of the parts when an imperfection in the fabric is encountered by the detector or loop-catching device;

Fig. 7 is a plan view of the detector or loop-catcher and its holder or sheath; and

Fig. 8 is a perspective view of the detector or loop-catcher.

In machines of the present and similar types various devices are employed for actuating the stopping mechanism when the yarns or other strands break or their supplies become exhausted. When the individual yarn supplies are comprised of multiple strands, for example, doubled yarns, it often happens that a single strand becomes broken and looped or tangled in the fabric to cause a fault or defect which impairs the quality of the finished product. It is therefore desirable to arrest the operation of the machine immediately such a fault occurs in order that the operator may remove the defect and repair the fabric.

For this purpose the present invention contemplates the use of a device for initiating the action of the stopping mechanism of the machine when single strands of the multiple ends break and cause loops, tangles or bunches projecting from the fabric, or when such faults occur from other causes. The device comprises, in general, a detector or loop-catcher which is arranged in close proximity to the fabric adjacent the point where the yarns are applied thereto. When an imperfection occurs in the fabric the detector is engaged by the looped or tangled end and moved into position to close an electrical circuit to a solenoid. The solenoid constitutes the controlling element for actuating the stopping mechanism of the machine.

The present drawings illustrate the invention as applied to a braiding machine of the same general type as that shown and described in U. S. Letters Patent No. 1,602,442, granted to Thomas Miller, October 12, 1926. The machine comprises a base 5 mounted upon a bed 6 which is supported from the floor by legs 7. Turrets or heads 3 and 4 are revolvable in opposite directions upon the base 5 and carry supply-bobbins B or other packages of yarn, thread, cord or the like from which the strands s lead. The strands s

lead upwardly from the bobbins B under tension to the braiding point, indicated at 9, where they may be braided into a tubular fabric, for example, to cover a core C fed upwardly axially 5 of the machine by means of a suitable take-up reel or capstan 10. The capstan 10 is rotatably mounted upon a stud 11 fast in a cross-strut 12 extending diagonally across the top of the machine and supported by standards 13 rising from 10 the bed 6. In other instances the tubular fabric may be braided without a core.

Secured to one side of the base 5 is a bearing bracket 15 in which is journaled the main drive-shaft 16 of the machine. The shaft 16 projects 15 beyond the outer end of the bearing bracket 15 and carries an axially slidable drive-pulley 17 which may be driven by a belt connected to a suitable source of power. Secured fast to the inner end of the shaft 16 is a bevel-gear 18 which 20 meshes with large ring-gears, shown and described in the patent previously referred to as carried by the turrets 3 and 4 for revolving the latter in opposite directions on the base 5. Referring to Fig. 2, the rearward side of the bearing bracket 15 is formed with a housing 22 in which is a spur-gear 20. The gear 20 is keyed to a shaft 21 extending in parallel relation to the drive-shaft 16 and journaled in one side of the housing 22 and in a lateral projection 23 of 25 the bracket 15. The gear 20 meshes with a pinion-gear 25, fast on the main driving shaft 16, from which it is driven, see Figs. 2, 3 and 4.

Secured fast to the shaft 21 is a spur-gear 23 which meshes with a similar gear 28 fast on a 30 shaft 30, see Fig. 1. The shaft 30 is journaled in bearings at the lower end of a yoke 31, shown in Fig. 2, pivotally mounted on and depending from the shaft 21. To the projecting end of the shaft 30 is secured a sprocket 35 which drives 35 a similar sprocket 36 through means of a chain 37. The sprocket 36 is fast on one end of a shaft 38 journaled in a bracket 39 fastened to one of the legs 7 of the machine stand. A pinion-gear 45 fast on the opposite end of the shaft 38 meshes 40 with a larger gear 46 carried by a counter shaft 48 journaled in a bearing 49 of the bracket 39.

Fast on the shaft 48 is a small sprocket 50 which drives a larger sprocket 41 located thereabove by means of a chain 52. The sprocket 51 50 is secured to a capstan drive-shaft 55 journaled in a bearing 56 formed integral with the cross-strut 12. The shaft 55 carries a bevel-gear 57 which meshes with a relatively large ring-gear 58 attached to the side of the capstan or take-up wheel 10. Through the train of gearing and chain-drives described above the capstan 10 is rotated from the main driving shaft 16 at a greatly reduced rate of speed.

Referring to Fig. 2 of the drawings, the drive-pulley 17 may be rotatively connected to the shaft 16 by any suitable means such as a clutch-member 60. The clutch-member 60 is pinned to the outer end of the shaft 16 and provided with an annular, tapered rim 61 adapted to engage with 65 a correspondingly tapered internal face 62 on the pulley 17. The hub of the pulley 17 is provided with a flange 64 and adjacent thereto on the shaft 16 is rotatably and slidably mounted a collar 65 having pockets 66 in which are compression-springs 67 arranged to bear against a 70 collar or washer 68 abutting the end of the shaft-bearing 15 to urge the pulley into driving engagement with the clutch-member 60. Extending alongside the bearing 15 is a shipper-arm 70 75 provided with a yoke 71 at its outer end formed

with lugs 72 on its sides, shown by dotted lines in Fig. 2. The lugs 72 straddle the sides of the flange 64 on the hub of the driving pulley 17 to provide for sliding the latter longitudinally of the shaft 16. The shipper-arm 70 is formed with 5 a guiding slot 73 engaged by a boss or projection 74 on the side of the bearing bracket 15. At its opposite end the shipper-arm 70 carries an eye-bolt 75 by means of which it is pivotally connected to a knock-off device, to be later described, 10 for controlling the operation of the clutch-mechanism.

The exterior of the base 5 of the machine is formed with a cylindrical, flanged seat 79, see Fig. 1, on which is mounted a brake-ring 77. The 15 brake-ring 77 is adapted to be rotated to a slight extent on the base 5 and moved upwardly by instrumentalities, to be later described, which are actuated automatically upon relief of tension on the strands s being braided, caused by breakage 20 thereof or exhaustion of the supply. The rotative movement of the brake-ring 77 effects the operation of the above-mentioned knock-off device for disconnecting the driving means and the ring is also moved upwardly to cause it to 25 wedge against and arrest the rotation of the turret 4.

The stopping mechanism of the machine may be of conventional type and, as illustrated in Fig. 2, it comprises a spring 78 anchored at one end 30 to the boss 74 of the bracket 15. The opposite end of the spring 78 is connected to one arm 32 of a stopping lever 80 pivoted on a stud 81 projecting upwardly from an extension of the bracket 15. A second arm 33 of the lever 80 is pivotally connected at 84 to the eye-bolt 75 carried by the shipper-arm 70. A starting lever or handle 85, also pivoted on the stud 81, has a toe 85 adapted to engage a shoulder 89 on the lever 80 to rock the latter against the tension 40 of the spring 78 whereby to move the shipper-arm 70 to effect the clutching action in starting the machine. The lever 80 is locked in the position shown in Fig. 2, to render the machine operative, by means of a detent-latch or pawl 86. 45 The pawl 86 is pivoted to an arm 88 of the lever 80 by a pin 87 and is provided at its free end with a hardened block 89, one edge of which is adapted to engage a shoulder 90 of a lock-pin 91 fast in the top of the bracket 15, see Fig. 2. 50 A spring 96 having one end connected to the latch 86 and its opposite end anchored to an arm 97 on the lever 80 tends to maintain the latch 86 engaged with the detent-pin 91.

An arm 92 bolted to the brake-ring 77 projects 55 radially outward therefrom above the bracket 15 and is formed with a beveled or angular edge 93 at its end. The purpose of this latter construction is to provide means for releasing the detent-pawl 86 by the rotary movement of the brake-ring 77 in the manner as later explained. A link 93 connected at one end to a pin 94 on the arm 92 has its opposite end pivotally connected to the pivot-pin 87 on the arm 88 of the stopping lever 80. The link 93 functions to continue the movement of the brake-ring 77 during the counter-clockwise rocking movement of the lever 80 under the action of the spring 78.

To actuate the stopping mechanism to declutch the driving pulley 17 and arrest the rotation of 70 the turrets 3 and 4 the pawl 86 on the stopping lever 80 is released from engagement with the lock-pin 91 either by the mechanical means last described or by electrically controlled means as later described. A knock-off plate 100, shown in 75

Figs. 2, 3 and 4, is provided at one end with an upstanding pin 101 which is engageable with the beveled end of the detent-pawl 86. The plate 100 rests upon the top of the bracket 15 and has an elongated slot 102 at one end through which the detent-pin 91 projects whereby to provide for sliding movement of the plate with respect to the pin. The opposite end of the plate 100 is hingedly connected at 103 to the upper arm 104 of a bell-crank lever 105, see Figs. 3 and 4. The bell-crank lever 105 is pivotally mounted on a pin 106 held in an angle-iron 108 which is secured to the side of the housing 22 of the bracket 15 by means of a bolt 109. One end of the horizontal leg of the angle-iron 108 rests upon the top of the housing 22 while its opposite end is extended laterally to form a shelf 110 adapted to seat upon the top of the bracket 15 and provided with a circular hole through which the detent-pin 91 projects. The knock-off plate 100 is adapted to be slid along the shelf 110 by means to be next described to cause its pin 101 to wedge against the beveled end of the pawl 86 to disengage its block 89 from the detent-shoulder 90.

Pivoted to the arm 113 of the bell-crank lever 105 at 111 is a depending dog 112, the lower end of which is adapted to make contact with the periphery of a toothed wheel 114 secured fast to the shaft 21, previously described, and continuously rotated therewith in a clockwise direction as viewed in Figs. 3 and 4. The lower end of the dog 112 is held free from engagement with the teeth of the wheel 114, during the normal operation of the machine, by means of a link 115 which is hooked into a hole in the upper end of the dog. Under the action of means to be later described the link 115 is moved to rock the dog 112 on its pivot 111 to carry its lower extremity into engagement with the teeth of the wheel 114. The dog 112 is formed with upper and lower stop-lugs 116 which engage against the sides of the arm 113 of the bell-crank lever 105 in the manner illustrated in Figs. 3 and 4 to limit the pivotal movement of the dog with respect to the lever.

The link 115 is slidable through a slot in the vertical leg 117 of an angular sheet-metal bracket 118 secured to the top of the angle-iron 108 and is pivotally connected to the end of a plunger-rod 121 by a pin 122. The link 115 is urged toward the right as shown in Fig. 3 by means of a coil-spring 123 to withhold the lower end of the dog 112 from engagement with the toothed wheel 114. The spring 123 surrounds the link 115 with one end bearing against the leg 117 of the bracket 118 and its opposite end held by a washer 124 carried by the link.

The dog 112 is rocked to engage its lower end with the teeth of the wheel 114 by sliding the link 115 toward the left, a solenoid 125 attached to the side of the housing 22 by screws 126 being employed for this purpose. The solenoid 125 is provided with a slidable plunger or armature 127 adapted to be drawn into the solenoid when the latter is energized. Inward sliding movement of the plunger 127 causes the rod 121 and link 115 to be slid against the action of the spring 123 to swing the lower end of the dog 112 into engagement with the wheel 114. This latter movement is terminated when the upper stop-lug 116 strikes against the bell-crank lever 105. As the wheel 114 rotates in the direction indicated by the arrows in Figs. 3 and 4 one of its teeth will engage with and raise the dog 112 bodily in the manner indicated by dash-lines in Fig. 4. The lifting of the dog 112 acts to rock the bell-crank

lever 105 in a counterclockwise direction, thereby by sliding the plate 100 toward the left as viewed in Fig. 4 whereby to force its pin 101 against the beveled end of the pawl 86 to pry the latter away from the detent-pin 91. Upon release of the pawl 86 the stopping mechanism is actuated to arrest the operation of the machine in the manner as hereinafter more fully explained.

Means as usually provided for stopping the machine when a yarn breaks or its supply is exhausted are shown and described in United States Letters Patent No. 1,085,369 dated January 27, 1914, and, as herein illustrated, may comprise a series of vertically slidable plunger-pins 129 disposed in spaced relationship around the turret 4. The plungers 129 are actuated under the control of tension-devices acting on the strands during the braiding or other operation of the machine. When the tension is relieved upon breakage of a strand or exhaustion of its supply one or more of the plungers 129 will be depressed into position to engage the upper end of a lever 130, see Figs. 3 and 4, pivoted on a stud 131 fast in a plate 132 secured to the base 5. At one end of the plate 132 is an upstanding ear or lug 136 formed with an angularly-inclined face 137 adapted to make contact with a similar inclined face 138 on a plate 139 fastened to the brake-ring 77 by a screw 140 which projects forwardly through a slot 143 in the lever 130. The two plates 132 and 139 serve as wedge-blocks, their angular faces being brought into engagement when the brake-ring 77 is rotated to cause the latter to be lifted to engage its inner tapered face with the tapered periphery or brake-surface 76 on the turret 4. As the brake-ring 77 is rotated the angular edge 93 of the arm 92 is moved into position to engage the beveled end of the pawl 86 to pry the latter away from the pin 91 and disconnect the drive for the machine. A plurality of the cooperating plates or wedge-blocks 132 and 139 are preferably employed on the machine, being arranged at intervals around the circumference of the base 5, whereby to equalize the lifting force on the latter in applying the brake.

Secured to the brake-ring 77 by means of a screw 144 is an angular bracket 145, see Figs. 3 and 4, constructed of fiber or other dielectric material. The bracket 145 has a right-angle extension or arm 146 provided with a threaded hole 50 for receiving an adjustable contact-screw 147. A check-nut 148 on the screw 147 holds the screw 147 in its adjusted position. A flexible wire 193 having one of its ends secured to the screw 147 by means of the nut 148 extends upwardly to the detector or loop-catcher 165 to be later described. Attached to the side of the base 5 by means of a screw 152 is a fiber bracket 153 similar in construction to the bracket 145. A leaf-spring 154 secured to the side of the bracket 153 reaches upwardly therefrom and carries a contact-screw 158 which is normally in engagement with the contact-screw 147, as shown in Fig. 3, during the operation of the machine. A wire 149 having one of its ends secured to the screw 158 by means of a nut 159 has its opposite end joined to a terminal 150 of the windings of the solenoid 125. Electrical current is supplied to the solenoid windings from a suitable source, not herein shown, through a circuit including a conductor 160 and with the two elements 147 and 158 in engagement the circuit is completed to the detector or loop-catcher by way of the wires 149 and 193.

In applying a fabric covering to electrical conductors, rubber hose and other flexible tubing or

the like, the yarn strands are usually composed of multiple ends wound in parallel relationship. For the purpose of arresting the operation of the machine when a single end of any multiple-end strand breaks and becomes looped in the fabric, or when a snarl or tangle appears therein from any cause, the present invention comprises a detector-device which acts automatically to close the electrical circuit, before described, whereby to energize the solenoid 125 and stop the machine.

Referring to Figs. 1, 5 and 6, the detector-device, indicated generally by the reference character 165, is mounted for vertical adjustment on an arm 166 secured to the cross-strut 12 of the machine frame by means of bolts 161. The arm 166 is provided at its lower end with a split hub 168 bored to receive a vertical rod 169. A mounting 170 formed with a hub 171 at one end is adjustably secured to the lower end of the rod 169 by means of a set-screw 172, see Figs. 5 and 6. The mounting 170 is formed with a vertical bearing 173, in which is journaled a hollow spindle 175. The spindle 175 has a flanged head 176 which seats upon the upper end of the bearing 173 and an axial bore 177 through which the fabric F feeds upwardly to the take-up capstan 18. Secured to the upper end of the spindle 175 by means of screws 178 is a bevel-gear 179 arranged in mesh with a bevel-pinion 180 fast on a shaft 181 journaled in a bearing hub 182 on the mounting 170 and extending at right-angles to the spindle 175. Fast on the opposite end of the shaft 181 is a sprocket 183 which is driven from a larger sprocket 184 on the capstan-shaft 55, previously referred to, by means of a chain 185, see Fig. 1.

Fastened to the under side of the head 176 of the spindle 175 in any suitable manner is a fiber washer or annulus 188 which carries a metal contact-ring 187, preferably constructed of brass, on its under side. The contact-ring 187 is rotated with the spindle 175 to adapt it to wipe across the end of a carbon brush 189 slidably mounted in a holder 190 fastened to the side of the bearing 173 and insulated therefrom by a fiber strip 191. The brush 189 is urged upwardly against the contact-ring 187 by a coil-spring 192 pocketed in the holder 190. The wire 193, previously described as having one end joined to the contact-screw 147, has its opposite end attached to the holder 190. A pin 195 riveted to the contact-ring 187 projects upwardly through an insulating bushing 194 inserted in a bore in the head 176 of the spindle 175 and in the gear 179.

The spindle 175 is provided at one side with a small vertical bore 197 extending parallel to its axis throughout its length for slidably receiving a push-rod 196. The upper end of the bore 197 is counterbored to receive the flanged head of a metal sleeve 198, the reduced portion of which is slidable through a hole in the gear 179. The upper extremity of the sleeve 198 is threaded to receive an internally threaded fiber coupling 199. Screwed into the upper end of the coupling 199 is a contact-screw 200 which is held in adjusted position in the coupling by means of a check-nut 201. A wire 202 is connected to the upper threaded portion of the pin 195 by means of a nut 203 and spaced from the top of the gear 179 by a fiber washer 204. The opposite end of the wire 202 is connected to the contact-screw 200 between the nut 201 and the end of the coupling 199.

Detachably mounted on a reduced lower portion of the spindle 175 is a thimble or cap 208. The thimble 208 comprises a cylindrical shell portion which surrounds the reduced end of the spindle and a lower annular portion 209 of less diameter having an axial hole through which the fabric F feeds. A pin 210 held in the lower end of the spindle 175 projects radially outward to engage in a bayonet slot 211 in the thimble 208, see Figs. 1, 5 and 6 to provide for quick application and detachment of the thimble without the use of tools.

Slidable within the annular portion 209 of the thimble 208 is a cylindrical bushing or sheath 212, the lower end of which is rolled inwardly to form a flange engaging the lower end of a tubular loop-catcher 215, see Figs. 5 and 8. The loop-catcher 215 is held within the sheath 212 by means of an annular metal disk 216 fastened to the upper end of the sheath with its inner rim overlying the upper end of the loop-catcher. The disk 216 is of appropriate diameter to cause its rim to underlie the lower end of the wire push-rod 196. The disk 216 is formed with a plurality of spaced rectangular holes for receiving similarly shaped projections 217 formed on the upper end of the sheath 212 and riveted over against the top of the disk in the manner as shown in Fig. 7. The three parts 216, 215 and 212 of the loop-catcher are thus connected together to form a unitary structure adapted for vertical sliding movement within the thimble 208. The sheath 212 has a close fit within the thimble 208 to provide that when the spindle 175 is rotated the sheath will be likewise revolved about the fabric F for a purpose as later explained.

The tubular loop-catcher 215, shown in detail in Fig. 8, is provided with a plurality of inwardly-projecting pointed teeth or prongs 220. The prongs 220 are preferably formed by slitting the metal obliquely and bending the metal between the slits inwardly. As shown in Fig. 8, the prongs 220 are arranged with their pointed ends projecting in the direction in which the catcher 215 rotates as indicated by the arrow in Fig. 7. The method of operation of the complete machine will next be explained.

To prepare the braiding machine for operation a core C such as a wire or other conductor may be drawn upwardly axially of the machine, passed through the detector-device 165 and coiled several times around the capstan 18; from which point it is led to a suitable reel or drum, not herein shown, to reel up the finished product. A suitable number of bobbins B are placed on the carriers on the turrets 3 and 4 and the yarns or other strands s led through the tension-devices, indicated at 19 in Fig. 1, with their ends attached to the core C at the braiding point 9. For the purpose of the present explanation it may be assumed that each strand s is composed of a plurality of ends arranged in parallel relationship.

The machine is started to operate by swinging the starting handle 85 in a clockwise direction, as viewed in Fig. 2. The lever 80 is rocked from the handle 85 to engage the latch or pawl 86 with the shouldered detent-pin 91. At the same time, through the link 93 and arm 92, the brake-ring 92 is rotated in counterclockwise direction, as viewed in Fig. 2, to move the contact-screw 147 into engagement with the contact-screw 158. The contact made at this point completes the branch of the circuit comprising the wire 149 and the wire 73.

193 connected to the detector-device 165. The rocking motion of the lever 80 also slides the shipper-arm 70 toward the right, as viewed in Fig. 2, to cause the driving pulley 17 to be engaged with the clutch-member 60. The driving connection thus effected between the pulley 17 and shaft 16 causes the bevel-gear 18 to transmit motion to the gears on the turrets 3 and 4 to rotate the latter about the axis of the machine. As the heads 10 or turrets 3 and 4 are rotated in opposite directions in accordance with the usual arrangement in machines of this type, the supply bobbins B are revolved about the feeding core C and the strands s are manipulated by suitable means, not herein shown, to pass them over and under one another to enmesh them in the fabric covering F.

The machine is thus driven to braid the strands s onto the core C, but upon breakage of a strand, exhaustion of its supply, or when an imperfection occurs in the fabric its operation is automatically arrested in the manner as next explained. When a strand s breaks, or its supply runs out, the plunger 129, controlled by the appropriate tension-device 19 through which that particular strand draws, is projected into the path of the offset portion 142 of one of the levers 130. The rotation of the turret carrying the plunger 129 will cause the latter to wipe across the upper end of the lever 130 to swing it on its pivot 131 in a counterclockwise direction as viewed in Figs. 3 and 4. The rocking action of the lever 130 transmits rotative movement to the brake-ring 77 through its screw-and-slot connection 140 and 143. This rotative movement of the brake-ring 77 engages the angular edge 98 of the arm 92 with the beveled end of the pawl 86 and releases the latter from the lock-pin. The rotary movement of the ring 77 is then continued by the spring 78 acting through the lever 80 and link 93 to carry the wedge-blocks 139 into engagement with the stationary wedge-blocks 132 on the base 5 to apply the brake to promptly arrest the operation of the machine.

In addition to the means for arresting the operation of the machine when a strand breaks or its supply is exhausted, the detector-device of the present invention provides means for stopping the machine when an imperfection occurs in the fabric. The spindle 175 together with its connected parts is rotated about the fabric F just above the point at which the yarns are merged thereinto and the sheath 212 and pronged loop-catcher 215 are rotated therewith. The pointed ends of the prongs 220 on the loop-catcher 215 are thus revolved about the fabric with a clearance of a few thousandths of an inch and during normal operation of the machine, while the strands mesh in the fabric without fault, the loop-catcher remains in its lowermost position with the push-rod 196 resting upon the disk 216 as illustrated in Fig. 5. During this relationship of the parts the lower end of the contact-screw 200 clears the upper end of the rod 196. If, however, a loop or snarl is formed in the strands as they are enmeshed in the fabric, for example as indicated at b in Fig. 7, one of the prongs 220 of the loop-catcher 215 will catch the loop and as the fabric feeds upwardly it will lift the loop-catcher with it.

As the loop-catcher 215 is drawn upwardly in the thimble 208 the disk 216 is raised with it to force the rod 196 upwardly into contact with the screw 200. The contact made at this point will thus close the branch circuit from the wire 193 through brush 189, ring 187, pin 195 and wire 202 to the rod 196 which is grounded in the spindle 175. The

electrical circuit is thus completed through the ground in the frame of the machine to energize the solenoid 125 which causes it to exert a pull upon the plunger 127. As the plunger 127 is slid into the solenoid 125 the rod or link 115 connected thereto is forced from the position shown in Fig. 3 to that illustrated in Fig. 4 against the action of the spring 123. This movement of the link 115 rocks the knock-off dog 112 to swing its lower end into position to be engaged by the teeth 114 of the rotating wheel 114. The movement of the dog 112 in this direction is limited by the engagement of its upper lug 116 with the side of the bell-crank lever 105. As the wheel 114 rotates in the direction indicated by the arrow in Fig. 4 one of its teeth strikes the end of the dog 112 to raise the latter bodily and thereby rock the lever 105 in a counterclockwise direction in the manner indicated in Fig. 4. The knock-off plate 100, connected to the upright arm 104 of the lever 105, is thus slid laterally to cause its pin 101 to engage the beveled end of the pawl 86 to pry the latter away from the detent-pin 91.

Upon release of the detent-latch 86 the spring 78 acts to rock the stopping lever 80 to draw the shipper-arm 70 toward the left, as viewed in Fig. 2, and through the engagement of its yoke 71 with the flange 64 on the pulley 17 the latter is withdrawn from engagement with the clutch-member 60 to disconnect the drive. As the lever 80 is moved to declutch the drive-pulley 71 it acts through the link 93 to impart rotative movement to the brake-ring 77 on the base 5. The force of the spring 78 is thus applied to the brake-ring 77 to cause its wedge-blocks 139 to continue to 35 coact with the fixed wedge-blocks 132 to frictionally engage the ring with the braking surface 76 on the turret 4. This wedging action of the brake-ring 77 is augmented by the rotation of the turret 4 which, by its frictional engagement with the ring, tends to force the wedge-faces 137 and 138 into firmer contact to effect prompt arrestment of the operation of the machine.

As the brake-ring 77 and its connected parts are rotated to arrest the operation of the machine the contact-screws 147 and 158 are separated in the manner indicated in Fig. 4, whereby to open the solenoid circuit. This provision for breaking the circuit to disrupt the flow of electrical current saves current when the machine is inoperative and prevents overheating and burning out the windings of the solenoid, or of a transformer when the latter is employed in the circuit.

After the operation of the machine is arrested the operator or attendant may slide the spindle 175 upwardly in its bearing 173 by raising the thimble 208. The thimble 208, loop-catcher 215 and its connections may thus be withdrawn from the last fabricated portion of the fabric to uncover the fault or defect therein so that it may be cut out or repaired. Thereafter, the detector parts may be lowered again into operative position and the machine restarted by merely shifting the starting handle 85.

It will be observed from the foregoing that the present invention provides an improved construction of controlling mechanism for application to braiding, knitting and like machines wherein strands are enmeshed to form a fabric. 70 The improved device acts mechanically to inspect the product of the machine and detect faults therein adjacent the point of fabrication so that when the operation of the machine is arrested the imperfections may be readily corrected by the 75

operator without necessitating removal of a large portion of the fabric.

The device operates with equal efficiency in detecting looped strands, enlargements or other imperfections in the fabric and acts automatically to promptly arrest the operation of the machine upon occurrence of such faults. The detector or loop-catcher is extremely sensitive and positive in action, being light in weight to adapt it to be moved easily by the upward feed of the fabric to initiate the operation of the stopping mechanism of the machine.

With the use of the present improved device multiple-end yarns may be braided or knitted into the fabric and the latter mechanically inspected to prevent the passage of loose ends thereinto so as to maintain the required ply. One end of a multi-ply yarn may become broken without releasing the appropriate stop element which will still be held by the remaining strand or strands; but when such a break occurs the end usually becomes snarled or looped in the fabric and thus the fault will be detected and the operation of the machine arrested by the present improved device.

Should a broken or exhausted supply strand be repaired without first drawing its end from the last-formed portion of the fabric, loops will appear in the fabric and will be immediately caught up by the loop-catcher to arrest the operation of the machine. Likewise, when broken ends are tied together with too large a knot, such a knot will be caught up by the detector or loop-catcher. In this manner the detector-device acts to inspect the operator's work and to prevent the passage of irregularities resulting from faulty piecing-up.

While the improved stopping mechanism is herein shown as applied to use on a braiding machine of certain type, it is to be understood that it may have other applications and the construction and arrangement of its parts may be varied without departing from the spirit or scope of the invention. Therefore, without limiting myself to the exact embodiment of the invention herein shown, I claim:

1. In a machine of the type indicated, means for combining a plurality of strands to form a tubular fabric, stopping means for arresting the operation of the machine, a loop-catcher surrounding the formed fabric and adapted to engage a loop or tangle projecting therefrom, and means operative by said loop-catcher to actuate the stopping means.

2. In a machine of the type indicated, the combination of means for forming a tubular fabric, stopping means for arresting the operation of the machine, a loop-catcher surrounding the formed fabric and having prongs for engaging loops or tangles projecting therefrom, and means operative by the loop-catcher to actuate the stopping means.

3. In a machine of the type indicated, means for combining strands to form a tubular fabric, stopping mechanism for arresting the operation of the machine, an annular member enclosing the formed fabric and adapted to engage loops or tangles projecting therefrom, said member being movable by and with the fabric, and means operative by the movement of said member when engaged with a loop or tangle to operate the stopping mechanism.

4. In a machine of the type indicated, means for combining strands to form a tubular fabric, stopping means for arresting the operation of the machine, detent-means for normally maintaining the stopping means inactive, electrically-con-

5 machine, an annular detector rotatable about the fabric and having means for engaging loops or tangles therein, means for feeding the fabric past the detector, and means operative by the detector when engaged with a loop to actuate the stopping means.

5. In a machine of the type indicated, means for combining a plurality of strands to form a fabric, stopping means for arresting the operation of the machine, a loop-catcher formed with a plurality of prongs adapted to engage a loop projecting from the fabric and to be moved thereby in the direction of feed of the fabric, and means operative by the loop-catcher to actuate the stopping means.

6. In a machine of the type indicated, means for combining a plurality of strands to form a fabric, stopping means for arresting the operation of the machine, a loop-catcher having a plurality of prongs extending angularly toward the fabric and adapted to engage a loop or tangle projecting from the fabric and to be moved thereby in the direction of feed of the fabric, and means actuated by the movement of the loop-catcher to initiate the operation of the stopping means.

7. In a machine of the type indicated, means for combining strands to form a tubular fabric, stopping means for arresting the operation of the machine, means for feeding the formed fabric through the machine, an annular detector rotatable about the fabric, said detector having means for engaging defects in the fabric to be moved by and with the latter, and means operative by said movement of the detector to actuate the stopping means.

8. In a machine of the type indicated, means for combining strands to form a fabric, means for feeding the formed fabric through the machine, stopping means for arresting the operation of the machine, a bodily-movable detector surrounding the fabric and having means for engaging loops or snarls projecting therefrom, and means operated by the detector when the latter is moved with the fabric to actuate the stopping means.

9. In a machine of the type indicated, means for combining strands to form a tubular fabric, means for feeding the formed fabric through the machine, stopping means for arresting the operation of the machine, an annular detector surrounding the fabric and having inwardly-projecting prongs adapted to engage with loops or snarls thereon, means to rotate the detector about the fabric, and means operative by movement of the detector with the fabric to actuate the stopping means.

10. In a machine of the type indicated, means for combining strands to form a fabric, stopping means for arresting the operation of the machine, electrically-controlled means for actuating the stopping means, an electric circuit therefore, a detector surrounding the formed fabric and having means on its interior for catching loops or tangles projecting therefrom, said detector being adapted to be moved by and with the fabric in the direction of its feed, and circuit-closing means actuated by said detector for energizing the electrical means to actuate the stopping means.

11. In a machine of the type indicated, means for combining strands to form a fabric, stopping means for arresting the operation of the machine, detent-means for normally maintaining the stopping means inactive, electrically-con-

trolled means for releasing the detent-means, an electrical circuit therefor, a detector for detecting faults in the fabric, said detector enclosing the fabric and having means thereon for catching a loop or snarl therein whereby to be moved by and with the fabric in the direction of its feed, circuit-closing means operated by said detector, and means operative concurrently with the stopping means to open the circuit when the 10 operation of the machine is arrested.

12. In a braiding or like machine, means for forming a fabric, stopping means for arresting the operation of the machine, means for detecting faults in the formed fabric, comprising a member having an unyielding projection directed toward the fabric and adapted to catch in a loop or snarl of the yarn, said member being movable 15

by and with the fabric in the direction of feed of the latter when its projection catches in a loop or snarl, and means operative thereby to actuate the stopping means.

13. In a braiding or like machine, means for combining a plurality of strands to form a fabric, stopping means for arresting the operation of the machine, a detector positioned adjacent the formed fabric, comprising a cylindrical member surrounding the fabric and provided with a projection on its interior adapted to catch in a loop or snarl of the strands to cause said member to be moved by and with the fabric in the direction of feed of the latter, and means operative by the detector to actuate the stopping means. 15

WILLARD W. BARDSLEY.
